UNITED STATES PATENT OFFICE.

ASBURY B. HUTTON, OF INDIAN HEAD, PENNSYLVANIA.

COMPOUND FOR GREASE.

No Drawing.

Application filed April 18, 1922. Serial No. 555,241.

To all whom it may concern:

Be it known that ASBURY B. HUTTON, a citizen of the United States, residing at Indian Head, in the county of Fayette and State of Pennsylvania, has invented certain new and useful Improvements in Compound for Grease, of which the following is a specification.

This invention relates to a lubricating compound, particularly to a compound such as adapted to be used as cup grease.

The primary object of my invention is to provide a compound of the above stated character that is particularly adapted for use on automobiles, tractors and especially where high speed is desired, one that will not gum or become hard in the coldest weather. A compound of this nature is also adapted for use on roller bearings, ball bearings, crank pins, crank bearings, sliding cross heads, and shafting of all kinds.

A further object of my invention is to provide a compound of the above stated character, which consists of relatively few ingredients and a simple process of compounding same, and one that can be manufactured and placed on the market at a very low cost.

These and like objects of my compound will be better understood as the description proceeds and is specifically pointed out in the appended claims.

My compound consists of the following ingredients and proportions used, petroleum jelly, 8 ounces; white lead, 4 ounces;

graphite, $\frac{1}{2}$ ounce; sulphur, $\frac{1}{2}$ ounce; linseed oil, 1 ounce; and tallow, 2 ounces.

In the process of compounding the above ingredients, they are placed in a receptacle and heated to a melting point, after which same are placed in a mixer and mixed from 4 to 6 hours after which the compound is ready for use.

The cup grease of the above ingredients will always remain in a semi-liquid condition in the coldest of weather, thus allowing same to freely oil the bearings, shafting, etc., at all times.

While I have shown and described the preferred form of my invention, I realize that various changes may be resorted to, such as will fall within the spirit and scope of the invention, therefore, I do not wish to limit myself to the exact proportions of ingredients used and the method of compounding same.

What I claim as new for my compound and desire to secure by Letters Patent is:—

1. A lubricating compound comprising petroleum jelly, white lead, graphite, sulphur, linseed oil and tallow, as and for the purpose specified.

2. A lubricating compound comprising petroleum jelly, 8 ounces; white lead, 4 ounces; graphite, $\frac{1}{2}$ ounce; sulphur, $\frac{1}{2}$ ounce; linseed oil, 1 ounce and tallow, 2 ounces, and as for the purpose specified.

In testimony whereof I affix my signature.

ASBURY B. HUTTON.
